UNITED STATES PATENT OFFICE.

VICTOR FRANK VON LOSSBERG, OF NEW YORK, N. Y.

DESIGN FOR A STANDARD.

53,189.

Specification for Design.

Patented Apr. 8, 1919.

Application filed January 4, 1919. Serial No. 269,700. Term of patent 3½ years.

To all whom it may concern:

Be it known that I, VICTOR FRANK VON LOSSBERG, a citizen of the United States of America, and residing in the city, county, and State of New York, have invented a new, original, and ornamental Design for a Standard, of which the following is a specification, reference being had to the accompanying drawing, forming part thereof.

The figure constitutes a front elevation of a standard embodying my invention, and indicated by dotted lines are electric light

shade and carrier associated with the standard to illustrate by way of example a structure of which the standard forms one element. Other lamp shade arrangements may be used with the standard, and the latter may be used for suitable purposes other than an electric light standard.

What I claim is:

The ornamental design for a standard substantially as shown and described.

VICTOR FRANK VON LOSSBERG.
